Attorney

UNITED STATES PATENT OFFICE.

JOHN HAYES, OF BELLE VERNON, PENNSYLVANIA.

CUSPIDOR.

1,424,247.

Specification of Letters Patent. Patented Aug. 1, 1922.

Application filed January 23, 1922. Serial No. 531,261.

To all whom it may concern:

Be it known that I, JOHN HAYES, a citizen of the United States, residing at Belle Vernon, in the county of Fayette and State 5 of Pennsylvania, have invented certain new and useful Improvements in Cuspidors, of which the following is a specification, reference being had to the accompanying drawings.

10 This invention relates to certain improvements in cuspidors, and it is an object of the invention to provide a device of this general character which can be positioned or suspended at a location best suited for use and 15 which is also of a character to render the same sanitary.

Another object of the invention is to provide a novel and improved device of this general character comprising a bowl supported for swinging or tilting movement, together with means for maintaining the same in an upright or working position, the swinging or tilting movement of the bowl permitting the same to be readily and conveniently cleansed when the necessities of 25 practice may require.

Still another object of the invention is to provide a novel and improved device of this general character which may be conveniently and effectively cleansed without the necessity of a porter or other person bringing his hands in direct contact with the bowl and which in itself is of utmost importance from a sanitary point of view.

30 The invention consists in the details of construction and in the combination and arrangement of the several parts of my improved cuspidor whereby certain important advantages are attained and the device rendered simpler, less expensive and otherwise more convenient and advantageous for use as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view in side elevation of a 50 cuspidor constructed in accordance with an embodiment of my invention, the second position of certain of the parts being shown in elevation;

Figure 2 is a view in front elevation with 55 portions broken away of the device.

As disclosed in the accompanying draw-

ings, A denotes a base having extending upwardly from the central portion thereof a short post 1. Secured to the upper portion of the post 1 and extending laterally therefrom is an arm 2, the outer end portion of the arm having extending upwardly therefrom an elongated rod or member 3. This rod or member 3 serves as a handle to facilitate the transporting of the completed device when required and the upper portion of said rod or member is provided with an opening 4 whereby my improved device may be suspended from a wall or other support, as may be preferred.

Secured to the arm 2 and directly above the post 1 is a head 6 provided with a pair of upstanding, spaced, perforate ears 7. Fitting between the ears 7 is an ear or lug 8 depending from the bowl B and disposed through the ears 7 and the ear or lug 8 is a pin or bolt 9 whereby the bowl B is supported for swinging movement. Normally the bowl B is disposed in a vertical direction or substantially in parallelism with the rod 15 or member 3, and in order to prevent the bowl from swinging upwardly past a vertical center the rod or member 3 is provided with a stop member 10 with which the bowl B, when in its normal position, is adapted to have snug contact.

At a desired distance above the stop member 10, the rod or member 3 is provided with a pair of longitudinally spaced guide members or sleeves 11, through which is slidably disposed an elongated shank or rod 12. Encircling the shank or rod 12 between the members or sleeves 11 is a coiled spring 14, one end portion of said spring bearing against and having contact with the upper 20 guide member or sleeve 11, while the opposite end portion of the spring is secured, as at 15, to the shank or rod 12. By this means the shank or rod 12 is constantly urged downwardly. Extending outwardly 25 from the shank or rod 12 are the pins 16 which contact with the lower guide member or sleeve 11 to limit the downward movement of the shank or rod 12.

C denotes a cover or top member for the 30 bowl B herein disclosed as substantially concavo-convex, and is formed with its concave face upwardly disposed. The central portion of the cover member C is provided with a conventional opening and the peripheral 35 portion of said cover member C is secured to the lower portion of the shank or rod 12.

When the bowl B is swung upwardly into its normal or vertically disposed position, the same passes under the cover member C which, through the instrumentality of the 5 spring 14, is urged toward the bowl B and thus maintains said bowl B against accidental displacement. The spring 14, when the bowl is raised or lowered, will permit the cover member C to have the desired yielding 10 movement.

Extending outwardly in opposite directions from the lower portion of the bowl B are the arms 18 provided with upstanding fingers 19 with which are pivotally engaged 15 the extremities of a fork 20. The fork 20 is carried by an end portion of an operating handle H. The handle member H and the work, if preferred, can be made from a suitable bent wire or strand, although I do not 20 wish to be understood as limiting myself in this respect. The handle member H is of such length that when the bowl B is in its normal position said handle member can be caused to closely overlie the rod or member 3 25 and the outer or free end portion of the handle member H is provided with a loop or opening 21 which may also be engaged over the same member, such as a nail, with which the member or rod 3 is engaged when the device is suspended. By this arrangement further means is provided to prevent accidental tilting or swinging of the bowl B.

The handle member H provides a convenient means whereby the bowl B may be 35 swung downward when it is desired to cleanse the same and to tilt the bowl B to its normal position. With the use of the handle member H it will not be necessary for the porter or other person to touch the bowl B 40 with his hands.

From the foregoing description it is thought to be obvious that a cuspidor constructed in accordance with my invention is particularly well adapted for use by reason 45 of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out 50 my invention in practice except as herein-after claimed.

I claim:

1. A cuspidor comprising, in combination, a base, an upstanding member carried by the base to provide a handle for transporting 60 the cuspidor, a bowl supported by the base for swinging movement, a cover mem-

ber for the bowl, and means for yieldingly supporting the cover member by the upstanding member said means constantly urging the cover member toward the bowl when the bowl is underlying the cover member. 65

2. A cuspidor comprising, in combination, a base, an upstanding member carried by the base to provide a handle for transporting the cuspidor, a bowl supported by the base for swinging movement, a cover member for the bowl, means for yieldingly supporting the cover member by the upstanding member, said means constantly urging the cover member toward the bowl when the bowl is underlying the cover member, and a stop member carried by the upstanding member for limiting the swinging movement of the bowl toward the upstanding member to position said bowl below the cover member. 70

75 3. A cuspidor comprising, in combination, a base, an upstanding member carried by the base to provide a handle for transporting the cuspidor, a bowl supported by the base for swinging movement, a cover member for the bowl, a shank extending outwardly from the cover member and in parallelism with the upstanding member, guide members carried by the upstanding member through which the shank is slidably directed, and a 80 spring encircling said shank having one end portion secured to a guide member and its opposite end portion secured to the shank so that said spring member constantly urges the shank and the cover member toward the 85 bowl when the bowl is in an upright position. 90

4. A cuspidor comprising, in combination, a base, an upstanding member carried by the base to provide a handle for transporting the cuspidor, a bowl supported by the base for swinging movement, the lower portion of the bowl at opposite sides thereof being provided with upstanding fingers, an operating handle provided at one end portion with a fork, the extremities of the fork being pivotally engaged with the fingers of the bowl, the upstanding member being disposed through the fork. 95 100

105 5. A cuspidor comprising, in combination, a base, an upstanding member carried by the base to provide a handle for transporting the cuspidor, a bowl supported by the base for swinging movement, and an operating handle for the bowl, one end portion of said handle being provided with a form straddling the upstanding member, the extremities of the fork being pivotally engaged with the bowl. 110 115

120 In testimony whereof I hereunto affix my signature.

JOHN HAYES.
